UNITED STATES PATENT OFFICE.

JOHN G. MUELLER, OF DAYTON, OHIO.

RAIL-INSULATOR.

1,121,939.

Specification of Letters Patent. Patented Dec. 22, 1914.

Application filed September 28, 1914. Serial No. 863,791.

To all whom it may concern:

Be it known that I, JOHN G. MUELLER, a citizen of the United States, residing at Dayton, in the county of Montgomery and State of Ohio, have invented certain new and useful Improvements in Rail-Insulators, of which the following is a specification, reference being had therein to the accompanying drawing.

10 This invention relates to insulating devices for rail braces and the like.

The object of the invention is to provide a simple, inexpensive and highly efficient device for preventing the transmission of electric current from one rail to the other of a railroad track through the medium of rail braces or other connecting devices.

The rails of railroad tracks are now frequently used as electrical conductors forming parts of signal systems, and, in order to prevent interference with the circuit and the signals, it is necessary that the rails should be insulated one from the other. Consequently, wherever rail braces are used or other metallic connections are interposed between the rails, some means must be provided to insulate the rails one from the other. Such a device must be simple and inexpensive and of such a character that it will not only properly insulate the rails when it is first applied thereto, but that it will not be subjected to wear or breakage, which might eventually destroy or partially destroy the same and thus permit an electric connection between the rails. The device which I have designed has all these characteristics.

In the accompanying drawings Figure 1 is a sectional view taken transversely of the rails of a railroad track and longitudinally of a rail brace connecting the two rails; and Figs. 2 and 3 are detail views showing slight modifications of the insulating device.

In these drawings I have illustrated one embodiment of my invention and have shown the same in connection with a rail brace of a well known construction, but it will be understood that the invention is not limited in its use to this particular rail brace, or, in fact, to railroad rails, but may be used in connection with rails and connecting devices of various kinds.

In that particular embodiment of the invention here illustrated the rail brace comprises two rail-engaging devices, each of which consists of two clamping members, an outer clamping member 1 and an inner clamping member 2. These clamping members are constructed and arranged to engage the opposite flanges of the respective rails, and each clamping member is provided at a point beneath the base of the rail with a portion having an aperture 3 extending transversely to the rail. A connecting rod 4 extends through the apertures of the rail-engaging devices and is provided at its outer ends with fastening devices, such as nuts 5, adapted to draw the clamping members into firm engagement with the flanges of the rails. A spacing member, such as a sleeve 6, is arranged along the intermediate portion of the rod 4, and serves to space the inner clamping members 2 a proper distance apart and to hold them in firm engagement with the inner flanges of the rails.

In order to properly insulate the rod from the rails and thus prevent the same from transmitting electric current from one rail or the other, I have provided an insulating device which may be interposed between each of the rail-engaging devices and the connecting rod. Each of these insulating devices comprises a sleeve 7 arranged about that portion of the rod 4 which extends through the openings in the particular rail-engaging device to which the insulating device is to be applied. This sleeve is of such a thickness as to fit snugly in the space between the walls of the openings and the rod, thereby producing a snug fit but permitting the device to be readily assembled.

Arranged at the ends of the sleeve 7 are washers 8 and 9, the outer washer 8 being interposed between the fastening device or nut 5 and the adjacent end of the rail-engaging device. Preferably, a steel washer 10 is arranged between the fastening device and the insulating washer 8 to prevent undue wear upon the latter. The insulating washer 9 is interposed between the adjacent ends of the rail-engaging device and the spacing sleeve 6. Here also if desired, a steel washer 11 may be interposed between the insulating washer and the spac-

ing device. It will be understood, however, that these steel washers are used merely to save unnecessary wear and that the insulating device is complete without them.

5 The washers may be arranged differently relatively to the end of the sleeve, but I prefer to extend the ends of the insulating sleeve slightly beyond the opposite ends of the rail-engaging device and to mount the 10 insulating washers on the ends of the insulating sleeves, although this is not essential. In Fig. 2 I have shown the washer as arranged to fit about the rod 4 and having that portion of the opening adjacent to the 15 sleeve 7 enlarged or rabbeted to receive the adjacent end of the sleeve. In Fig. 3 I have shown a somewhat similar construction but have beveled the wall of the opening and tapered the end of the sleeve so that 20 these two parts may be drawn into firm engagement and caused to fit snugly one over the other.

The operation of the insulating device 25 will be understood from the foregoing description, and it will be apparent that the connecting rod and the spacing sleeve, which are the only parts extending between the rails, are insulated from the rails themselves, so that there is no possibility of electrical connection being established between 30 the two rails. Further, it will be apparent that the construction and arrangement of the insulating device is such that it is subjected to very little wear. None of the 35 weight of the train upon the rails is transmitted to the device and the arrangement is such that the vibration of the rails, due to the passing of the trains, will cause but little wear on the insulating device, and will 40 not be liable to break the insulation at any point. Further, it will be apparent that the device is very simple and inexpensive in its construction, thereby permitting it to be applied at a low cost.

45 The insulating material is commonly formed of compressed fiber or of other compositions which are more or less injured by continued exposure to moisture. When my insulating device is mounted on the rail brace, as above described, it would not ordinarily be injured by exposure to the weather, but there may be occasions or locations where it would be desirable to protect the same from moisture. When this is desired, I will inclose the sleeve, which extends beneath the rail, in a jacket of water proof material, such as sheet metal, as shown at 11 in Fig. 3, it being understood that the sheet metal lies wholly within the 55 washers so as not to form any electrical contact with the rod.

While I have shown and described one embodiment of my invention, it will be understood that this has been chosen for 60 the purpose of illustration only and that I

do not wish to be limited to the details of construction shown and described, as obvious modifications will occur to a person skilled in the art.

Having thus fully described my invention, 70 what I claim as new and desire to protect by Letters Patent, is:

1. The combination, with clamping devices adapted to engage the flanges on the opposite sides of a rail and having apertures arranged beneath said rail, a rod extending through the apertures in said clamping devices and adapted to hold the same in clamping engagement with said flanges, of an insulating sleeve 75 extending through both of said openings and surrounding said rod, the ends of said sleeve extending beyond the ends of said clamping devices, and washers of insulating material mounted on said projecting ends 80 of said sleeve.

2. The combination with devices adapted respectively to engage the two rails of a track and having openings extending transversely of said rails, a rod extending 90 through said openings, fastening devices on the outer ends of said rod and a spacing device extending along said rod between said rail-engaging devices, of means for insulating said rod from said rails, said means comprising sleeves surrounding those portions of said rod which extend through the openings in said rail-engaging devices, and extending beyond both ends of said devices, and washers mounted on the ends of said sleeves and interposed between the ends of the rail-engaging devices and said fastening devices and said spacing device, respectively.

3. The combination with devices adapted 105 respectively to engage the two rails of a track and having openings extending transversely of said rails, a rod extending through said openings, fastening devices on the outer ends of said rod and a spacing device extending along said rod between said rail-engaging devices, of means for insulating said rod from said rails, said means comprising sleeves surrounding those portions of said rod which extend through the 110 openings in said rail-engaging devices, and extending beyond both ends of said devices, and washers extending about said rod adjacent to the ends of said sleeves, the openings in said washers being enlarged on one side to receive the ends of 115 said sleeves.

4. The combination with devices adapted 125 respectively to engage the two rails of a track and having openings extending transversely of said rails, a rod extending through said openings, fastening devices on the outer ends of said rod and a spacing device extending along said rod between said rail-engaging devices, of means for insu- 130

lating said rod from said rails, said means comprising sleeves surrounding those portions of said rod which extend through the openings in said rail-engaging devices, and 5 extending beyond both ends of said devices, and washers extending about said rod adjacent to the ends of said sleeves, the openings in said washers being flared and the ends of the sleeves being tapered to engage the flared openings in said washers. 10

In testimony whereof, I affix my signature in presence of two witnesses.

JOHN G. MUELLER.
